UNITED STATES PATENT OFFICE.

HARRY A. CUMFER, OF CHICAGO, ILLINOIS, ASSIGNOR TO "GUYTON & CUMFER MFG. CO.", OF CHICAGO, ILLINOIS, A CORPORATION OF ILLINOIS.

SHINGLE-MAKING MACHINE.

Application filed January 5, 1925. Serial No. 538.

This invention relates to a shingle making machine through which a sheet of shingle material passes for shearing the same into a plurality of longitudinal strips and shearing the longitudinal strips into individual shingles.

The invention primarily concerns itself with novel mechanism for effectively separating the strips of shingle material in both horizontal and vertical planes before they reach the transverse shears that sever the individual shingles in order that the shears for one strip will not cut or damage an adjacent strip.

15 The invention comprises the novel structure and combinations hereinafter described and more particularly pointed out and defined in the appended claims.

20 In the accompanying drawings which illustrate a preferred embodiment of this invention and in which similar reference numerals refer to similar features in the different views:

25 Figure 1 is a side elevational view of a shingle making machine involving this invention.

Figure 2 is a fragmentary top plan view of the machine.

30 Figure 3 is an enlarged fragmentary longitudinal vertical sectional view of the machine taken upon the line 3—3 of Figure 2.

35 Figure 4 is an enlarged fragmentary horizontal sectional view through the machine, with the shingle material and parts in plan view, taken substantially upon the line 4—4 of Figure 3.

Figure 5 is an enlarged sectional view through the sheet shearing mechanism or slitters upon the line 5—5 of Figure 3.

40 Figure 6 is an enlarged vertical sectional view through the strip separating mechanism taken in a plane upon the line 6—6 of Figure 3.

45 Figure 7 is an enlarged broken sectional view through the rear draw rolls upon the line 7—7 of Figure 3.

Figure 8 is an enlarged bottom plan view of the transverse shears for shearing the individual shingles from the strips.

50 Figure 9 is a sectional view upon the line 9—9 of Figure 8, with the stationary shears added.

55 Figure 10 is an enlarged part sectional and part elevational view of the adjusting mechanism for the rotatable sheet shears

and the strip separating mechanism, upon the line 10—10 of Figure 3.

Figure 11 is a sectional view upon the line 11—11 of Figure 10.

Figure 12 is a plan view of the shingles as sheared from the strips.

As shown on the drawings:

Referring to the drawing, it will be observed that the machine comprises a suitable frame 1 which is preferably cast with pairs of upwardly extending spaced arms 2, 3, 4 and 5 upon its sides. The pairs of spaced arms on one side of the frame are in alignment with the corresponding arms on the other side of the frame. The pairs of arms 6 form guideways or bearing slides for the bearing boxes for the different shafts of the machine. Below the bearing boxes are depending lugs 6 in which adjustable screws 7 are mounted for adjusting the lower bearing blocks as is well known in the art.

70 The bearing box slides formed by the arms 2 retain the bearings for the slitter shafts 8 and 9 as shown in detail in Figure 5. In referring to said figure it will be observed that the shaft 8 is supported upon lower bearings 10 in contact with the screws 7, and the upper shaft 9 is journaled in the separable bearing blocks 11 and 12 the latter of which fits over the lower shaft 8. 75 The upper ends of each pair of arms 2 are connected by a slotted transverse member 13 through which a screw 14 extends. The lower end of each screw rests upon the bearings 11. A shaft 15 is journaled in the transverse members 13 and is provided with a pair of worms 16 (Figure 10) which mesh with worm wheels 17 upon the screws 14. Each shaft 15 is provided with a hand wheel 18 whereby the shaft may be rotated for 80

rotating the worm wheels 17 for adjusting the screws 14. The adjustment of the screws 14 will obviously adjust the shaft bearings as is well known in the art. Spaced blocks 19 are keyed upon the shafts 8 and 9, and cutting or slitting disks 20 are bolted or 85

screwed in any appropriate manner to the blocks 19 and are spaced apart the width of the desired strip of shingle material. The peripheries of the opposite disks upon the shafts 8 and 9 are in cooperative relation 90 and are adapted for slitting a sheet of roofing into a plurality of strips, (three in the present instance) as the same is passed therebetween. The shafts 8 and 9 are intergeared 95

by the gears 21 and a sprocket 22 on the end of the shaft 8 affords a means for rotating said shaft and imparting its rotation to shaft 9 through the gears 21.

5 The bearing box slides formed by the arms 3 retain the bearings for a pair of vertically spaced and parallel shafts 23 upon which the draw rolls 24 are secured between which the strips of roofing are drawn. The 10 strips of roofing which are denoted by the reference numerals 25 and 26 and 27 descend in the form of a loop 28 (Figure 3) to provide slack, and they then extend upwardly over a guide roll 29 to the strip separating 15 mechanism which is shown in detail in Figure 6.

In referring to Figure 6, it will be observed that a pair of vertically spaced and parallel shafts 30 and 31 are rotatably 20 mounted in adjustable bearings 10, 11 and 12 which are mounted in the guideways formed by the arms 4 and which are adjusted by a worm shaft 15, screws 14 and worm gear 17 as previously described in connection with the slitting mechanism. A pair 25 of grooved rolls 32 are secured upon the shaft 30. These rolls are spaced apart so that the distance between their respective grooves will be equal to the width of the 30 strips of roofing. A collar 33 is keyed upon the shaft 31 above each roll 32 and a strip separating disk 34 is screwed upon each collar. The peripheries or outer margins of these disks are wedge shaped and extend 35 into the grooves 35. In the particular construction illustrated, the inner sides of the disks are flat while the outer sides adjacent the peripheries are bevelled or wedge shaped. The peripheries of these disks extend 40 into the grooves 35 of the rolls 32 and exert an outward wedging action against the two outer strips of roofing 25 and 27. Consequently when the strips pass over the rolls 32, the disks 34 will rotate between the strips and separate the outer strips 45 25 and 27 from the intermediate strip 26, according to the thickness of said disks. The shafts 30 and 31 are geared together by suitable spur gears 36 one of which is driven in 50 a manner to be hereinafter set forth.

Beyond the strip separating mechanism is a pair of vertically spaced and staggered rolls 37 and 38 which are suitably supported by the frame as best shown in Figure 3. 55 These rolls are designed to temporarily separate or part adjacent strips of roofing. The intermediate strip of roofing 26 passes over the upper roll 37 while the strips 25 and 27 adjacent said intermediate strip pass under the roll 38. Consequently adjacent strips of roofing are temporarily vertically separated and any binding strands or threads not severed by the slitting mechanism or disks 32 are broken or torn apart 60 by this vertical separation.

From the vertical separating rolls 37 and 38, the strips of roofing pass between a pair of draw rolls 39 and 40 which are best shown in Figure 7. These rolls are secured upon the shafts 41 and 42 which are journalled 70 in suitable bearings retained in the guideways formed by the arms 5; the shaft 41 being journalled in the bearings 43 which contact the screws 7 and the shaft 42 being journalled in the bearings 44 which rest upon the bearings 43. The upper ends of the arms 5 are provided with caps or sockets 45 through which adjustable bearing screws 46 extend for engaging the tops of the bearings 44. Coil springs 47 surround the screws 80 between the bearings 44 and suitable abutments on said screws. The shafts 41 and 42 are intergeared by the spur gears 48 for simultaneous rotation. A sprocket wheel 49 is secured upon the shaft 41 and a sprocket 85 chain 50 is trained over said sprocket wheel and also over the aforementioned sprocket wheel 22 on the slitter shaft 8.

The draw rolls 39 and 40 feed the roofing strips to the transverse shears which consist 90 of a stationary shearing member 51 and a rotatable shearing member 52 keyed upon a shaft 53 which is suitably journalled in the frame of the machine.

The rotatable shearing member has a plurality of shearing plates 54 corresponding to the number of strips of roofing removably secured to the lower forward margin thereof as shown in Figure 8 and adjacent each shearing plate there is an additional shearing element 55 having a bevelled cutting edge. The end of each shearing plate 54 opposite the element 55 is correspondingly bevelled as indicated at 56; the bevelled edges being parallel to each other. 105

The stationary shears 51 comprise similar shearing plates 54 and elements 55 which are, however, reversely arranged with respect to the rotatable shears as shown in Figure 2. The outer face of the base of the stationary shears is of arcuate form as indicated at 57 in Figure 3 to provide rotatable space for the rotatable member of the shears. These shears are designed to cut the shingles 58 shown in Figure 12. 110

The sheared shingles are adapted to drop upon conveyor belts 59 which convey the same from the machine to any suitable point. These conveyor belts are trained over pulleys 60 secured upon a pair of spaced parallel shafts 61 and 62. 120

The main drive shaft 63 best shown in Figures 1 and 2 extends transversely of the frame in which it is suitably journalled. Power may be applied to this shaft by means 125 of a pulley 64. Adjacent the pulley, there is a small spur gear 65 that meshes with a large spur gear 66 (Figure 1) on the end of the rotatable shaft 53 that operates the transverse shears. The far end of the main 130

drive shaft 63 has a sprocket wheel 67 that drives the conveyor shaft 62 through the sprocket chain 68 and the sprocket wheel 69 on the conveyor shaft. The far end of the 5 shaft 53 carries a spur gear 70 (Figure 2) that meshes with an intermediate idler gear 71 which in turn drives a gear 72 on the far end of the roll shaft 42.

The spur gear 48 on the near end of the 10 roll shaft 41 meshes with an idler gear 73 supported on the side of the machine frame. The gear 73 drives the gear 36 on the shaft 30 that carries the separating grooved rolls 32.

15 It will accordingly be apparent that rotation of the drive shaft 63 will operate the conveyors and rotate the transverse shear shaft 53 which in turn through gears 70, 71 and 72 drives the draw rolls 39 and 40. The 20 lower roll shaft 41 drives the shafts 30 and 31 through the aforementioned gearing, and also the slitter shafts 8 and 9 through the sprocket gearing and spur gears 21. The vertical separating or parting rolls 37 and 25 38 are freely rotatable and are not connected to the driving mechanism.

From the foregoing, it will be apparent 20 that a valuable improvement has been made in connection with shingle machines of the type disclosed, in that the strips of shingle material or roofing are effectively separated and all connecting strands or threads are broken so that the shear plates for one strip will not damage an adjacent strip.

35 I am aware that many changes may be made and numerous details of construction may be varied through a wide range without departing from the principles of this invention, and I therefore do not purpose limiting 40 the patent granted hereon, otherwise than necessitated by the prior art.

I claim as my invention:

1. In a shingle machine, rotary slitters for shearing a sheet of roofing into strips, draw 45 rolls for advancing said strips, mechanism for effecting lateral separation of said strips and means for vertically and temporarily separating adjacent strips and a transverse shears for shearing said strips.

2. In a shingle machine, mechanism for 50 slitting a sheet of roofing and mechanism for laterally separating said strips comprising a pair of rotatable members, one of said members having a groove and the other member having a disk with a wedge-shaped 55 margin extending within said groove.

3. In a shingle machine, mechanism for 60 slitting a sheet of roofing and mechanism for laterally separating said strips comprising a pair of shafts, spaced grooved members upon one shaft, and disks with wedge shaped margins upon the other shaft for co-operation with said grooved members.

4. In a shingle machine, mechanism for 65 slitting a sheet of roofing and mechanism for separating said strips comprising a rotatable support for said strips having a groove, and a rotatable device adapted for rotating in the plane of said groove.

5. In a shingle machine, mechanism for 70 slitting a sheet of roofing and mechanism for laterally separating said strips comprising a rotatable shaft, a pair of spaced grooved members upon said shaft, a second rotatable shaft, a pair of disks upon said 75 second shaft, said disks having their outer side bevelled adjacent their peripheries, and the peripheries of said disks travelling in the grooves of said members.

6. In a shingle machine, the combination 80 with mechanism for slitting a sheet of roofing into strips, of mechanism for separating said strips comprising rotatable means for laterally shifting certain strips and vertically spaced rolling elements for guiding adjacent strips in different horizontal planes 85 after the lateral separation thereof.

7. In a shingle machine, mechanism for 90 shearing a sheet of roofing into strips, rolls for advancing said strips, mechanism for laterally separating said strips and means for temporarily and vertically separating adjacent strips after lateral separation thereof.

In testimony whereof I have hereunto 95 subscribed my name.

HARRY A. CUMFER.
